UNITED STATES PATENT OFFICE

EDGAR E. GREVE, OF BELLEVUE, PENNSYLVANIA, ASSIGNOR, BY MESNE ASSIGNMENTS, TO OIL WELL SUPPLY COMPANY, OF PITTSBURGH, PENNSYLVANIA, A CORPORATION OF NEW JERSEY

CASING ELEVATOR

Application filed September 7, 1929. Serial No. 390,891.

This invention relates to casing elevators, and particularly to casing elevators of the single bail and gate type of the class shown in my prior United States Patents No. 1,180,031 of April 18, 1916 and No. 1,618,653 of February 22, 1927.

Among the objects of the present invention are, to provide new and improved latch or locking means associated with the closure means of the elevator for automatically locking the closure; to provide a construction of such character as to permit a reversal of the body and associated parts when so desired in a simple and efficient manner, wherefore by the wear on the body and closure caused by the heavy loads to which these parts are subjected may be taken care of; and to provide a construction in which the loads carried by the elevator are so distributed as not to affect the proper working of the latch or lock actuating means.

In the accompanying drawings, which illustrate applications of my invention:

Fig. 1 is a top plan view of a casing elevator embodying my invention applied to a section of drill casing or pipe;

Fig. 2, a front elevation;

Fig. 3, a side elevation;

Fig. 4, a vertical sectional view taken 30 through the latch;

Fig. 5, a top plan view of the doors of the elevator, showing one door closed and another door engaging the latch cam;

Fig. 6, a top plan view of a modified form 35 of my invention.

Referring to the drawings, 2 designates the U-shaped body of the elevator, provided with diametrically opposed trunnions 3 for mounting a bail 4 to support the elevator 40 in the usual manner.

The open front of the body is adapted to be closed by means of doors or gates 5 and 5a, pivotally secured to the body by hinge bolts or pins 6, said doors and body being 45 provided with interfitting hinge portions 7. Doors 5 and 5a are also provided with interlocking portions 8 at their meeting edges to provide a firm and efficient closure. Handles 9 project outwardly from the doors for 50 the manipulation thereof.

One of the important features of my invention resides in new and improved locking or latching means for firmly securing the doors together. Midway of their joining edges, the doors 5 and 5a are provided with 55 projecting lugs 10 and 10a respectively, adapted to be engaged by a latch device including a member 11 having an opening 12 therethrough to receive the lugs. The latch device is further provided at its top with a 60 forwardly extending grip or handle 13 and an integral angularly disposed and inclined cam A projecting from a side thereof. A hollow cylindrical portion 14 depends from the latch proper, having a bore 15 adapted to receive a hollow cylindrical member 16. Member 16 is provided with an integral hub portion 17 having an opening 18 therethrough for receiving a transverse pin 19, the latter being rotatably mounted in spaced-apart 65 bosses or ears 20 disposed at the lower portion of the door 5. Hub 17 is fixedly secured to the pin 19 by means of a key 21.

The portion 14 of the latch is designed to have a reciprocal motion on the member 16. To this end, a latch spring 22 is positioned in the member 16 between an anchor pin 23, extending through the top of said member and an anchor pin 24, the latter extending through slots 25 formed in the lower portion 70 of member 16 and projecting at each side thereof into the wall of the portion 14. By means of the parts just described, the latch device is retained on the door 5 and is designed to move in a vertical direction substantially parallel to the vertical axis of the elevator. It will be noted that the spring 22 functions to draw element 11 always towards the lugs 10 and 10a.

Pin 19 is provided with a head 19a at 75 one end thereof and its other end extends beyond the boss or ear 20 and is slotted, as at 26, to receive one end of a coil spring 27, the other end of said spring extending downwardly against the outer surface of the door 5, as at 28. The action of the spring 27 is such that the latch device 11 is urged against the outer surface of the door 5, as shown; said spring, however, permitting movement of the latch structure away 80 85 90 95 100

from the doors and about the axis of the pin 19.

It will be noted that the lug 10a is formed with a recessed portions *a* at its top, for receiving the upper wall of the opening 12 of latch member 11 for retention thereof.

In positioning the elevator around the drill casing or pipe C, the doors are opened to permit the entrance of said casing to the cavity of the body 2. To close the doors 5 and 5a, the operator grasps the handles 9 and swings both doors inwardly toward the body. Cam A will engage lug 10a of the door 5a as the doors come together, and due to its downwardly inclined face *b*, said cam will lift the latch member 11 upwardly and outwardly with respect to the door 5, to which it is attached. When the latch opening 12 engages the lug 10a, the spring 27 will force the latch against the outer surface of the doors, and spring 22 with its cooperating pins and retainers will draw the latch downwardly in a direction substantially parallel to the vertical axis of the elevator, by means of the latch portion 14, until the upper wall of the latch opening 12 engages the recess *a*.

In the event that the door 5a is closed first, the upper wall of the latch opening 12 is tapered rearwardly and upwardly for engaging the outer edge of the lug 10a to lift the latch upwardly, whence it is moved inwardly by the spring 27 and downwardly into the recess *a* of said lug by means of spring 22, as described.

Should the door 5 be closed first, moving the door 5a inwardly will first engage the edge of said door with the cam face *b*, then lug 10a will engage the cam to effect a movement of the latch as hereinbefore described.

This condition is particularly shown in Fig. 5.

To open the doors, the operator grasps the grip 13 and lifts upwardly and then outwardly, to disengage the latch from the recess *a* of the lug 10a and permit the doors 5 and 5a to be swung open.

It will be noted that when the elevator is secured on the casing in closed position, the lugs 10 and 10a are within the opening 12 of the latch member 11. When a load is put on the elevator, the forces caused thereby which tend to open the elevator doors will be distributed and absorbed by the latch proper, which is member 11. No strain will be placed upon any of the members which serve to automatically operate the latch: in particular, the telescoping cylindrical members 14 and 16 and the transverse pin 19. It is noteworthy that the pivotal mounting of the pin 9 permits the locking means to be automatically moved or swung inwardly relatively to the body radially of the longitudinal axis thereof and substantially parallel to the said axis.

To insure efficient operation of my elevator, I have provided the doors 5 and 5a with

limiting lugs or projections 29, adapted to cooperate with similar lugs or projections 30 on the body 2, said lugs 29 and 30 being positioned adjacent the hinge pins 6. The function of these lugs is to provide a limiting means whereby the movement of the doors inwardly may be arrested, to insure alinement of the doors and their respective latch parts.

An additional feature of my invention consists of means for providing a reversible elevator; that is to say, an elevator which has two load-supporting surfaces for engaging the couplings of the drill casing sections. As shown in the drawings, the body and doors have an upper load-supporting surface 31 and a similar lower surface 32. In the upright position shown, the upper surface 31 is used for supporting the casing. For retaining the elevator in this position, I provide retaining members 33, each of said members having one end secured to the trunnion 3 by means of a bolt 34, and a right angle portion 35 projecting into an opening 36 in the body 2.

When it is desired to employ the lower surface 32, the bolts 34 may be loosened, and the portions 35 disengaged from openings 36. The entire elevator may then be turned through 180 degrees on the axis of its trunnions, and portions 35 entered into openings 36a of the body. Bolts 34 are then tightened and the elevator is ready for use in its inverted position.

In the form of Fig. 6, I have shown my latch applied to a single-door elevator. The cam A is not necessary to this construction, and is omitted. The lug 10a is secured to the body 2a and the lug 10 is formed on the single door 5b. The latch 11 is pivotally mounted on this door 5b. All other parts are similar to those shown in the preferred form of my invention. The operation of the latch on this form of elevator is similar to the two-door elevator when the door bearing the lug 10a has been closed first.

I claim:

1. In a casing elevator, a reversible body member having similar end portions, trunnions projecting from the body, a bail pivotally connected with the trunnions, said body being provided with a recess adjacent each end, and a body-retaining member having a portion entered in one of the said recesses.

2. In a casing elevator, a reversible body member having similar end portions, trunnions projecting from the body, a bail pivotally connected with the trunnions, and a body-retaining member having a trunnion-engaging portion and a body-engaging portion, said body member having at each end a portion for engagement by the retaining member, either of which may be engaged thereby selectively.

3. In a casing elevator, a reversible body member having similar end portions, trunnions

nions projecting from the body, a bail pivotally connected with the trunnions, closure means for the body, locking means for the closure including automatically operable means operable to effect locking upon movement of the closure means when the body is in either of two positions, and a body-retaining member having a trunnion-engaging portion and a body-engaging portion, said body member having at each end a portion for engagement by the retaining member, either of which may be engaged thereby selectively.

4. In a casing elevator, a reversible body member having similar end portions, trunnions projecting from the body, a bail pivotally connected with the trunnions, a pair of hinged gates mounted on the body, a lug on the respective gates adjacent the meeting edges thereof, locking means for said gates mounted on one of the gates, said locking means including automatically operable means operable to effect locking upon movement of the gates when the body is in either of two positions, and a body-retaining member having a trunnion-engaging portion and a body-engaging portion, said body member having at each end a portion for engagement by the retaining member, either of which may be engaged thereby selectively.

5. In a casing elevator, the combination with a bail, of a reversible body member having similar end portions, trunnions pivotally mounting the body on the bail, said body having a recess adjacent each of its opposite ends, and a body retainer element having one portion connected to a trunnion and another portion entered in one of said recesses.

6. In a casing elevator, the combination with a bail, of a reversible body member having similar end portions, trunnions pivotally mounting the body on the bail, said body having a pair of recesses adjacent each of its opposite ends, and a pair of body retainer elements each having one portion connected to a trunnion and another portion entered in one of said recesses.

7. In a casing elevator, a reversible body member having similar end portions, trunnions projecting from the body, a bail pivotally connected with the trunnions, said body being provided with a recess adjacent each end, and a body-retaining member having one portion connected to a trunnion and another portion entered in one of said recesses.

55. In testimony whereof I affix my signature.

EDGAR E. GREVE.
